UNITED STATES PATENT OFFICE.

HOWARD M. DUDLEY, OF PHILADELPHIA, PENNSYLVANIA.

DYEING-MACHINE.

1,258,203.

Specification of Letters Patent.

Patented Mar. 5, 1918.

Application filed December 5, 1916. Serial No. 135,115.

To all whom it may concern:

Be it known that I, HOWARD M. DUDLEY, a citizen of the United States, and a resident of Philadelphia, in the county of Philadelphia and State of Pennsylvania, have invented certain new and useful Improvements in Dyeing-Machines, of which the following is a specification.

My invention relates to a dyeing machine and refers particularly to a machine suitable for the dyeing or treating of warps in the ball or worsted tops in the ball.

One object of my invention is a machine adapted to dye vegetable or animal fibers evenly and uniformly.

Another object of my invention is a machine adapted to dye cotton warps in the ball or worsted tops in the ball in a uniform manner.

Another object of my invention is a machine whereby the condition of the fiber may be readily judged at any stage of the treating operation.

Another object of my invention is a machine whereby the dyeing, or other, liquid may be uniformly forced through the fiber without disturbing the fiber.

These and other objects of my invention will be evident upon a consideration of my specification and claims.

The principal object to be obtained in dyeing textile fibers in an inclosed receptacle is the uniform passage of the dye liquor through all parts of the fibers, in order that the entire mass may be subjected to the same quantity of the liquor. It is further advisable that the temperature of the dye liquor be readily determined and easily controlled, as the most effective results of different dyes are obtained at different temperatures. It is further advisable to be able to readily and accurately determine the condition of the dyed goods at any stage of the operation, without disturbing the mass.

These and other evident advantages are possessed by the dyeing machine of my invention.

In dyeing machines of this character it is necessary that the fibers be maintained within a perforated or foraminous receptacle

and that the dye liquor be forced through these perforations in such a manner that all parts of the fiber are subjected to equal treatment.

I have found that the main difficulty incident to the even dyeing of fibers in such machines is due to the fact that when the dye liquor is forced into the goods through tubular openings, the liquor has the natural tendency to penetrate the fiber mass in direct streams from the opening, thus subjecting some portions of the fibers to more dye liquor than other portions, resulting in uneven dyeings.

I have further found that this difficulty may be overcome, and that all the fibers may be subjected to equal treatment if the perforations are of a conical or expanding shape of such a formation that the dye liquor instead of impinging upon the fibers in a series of separate streams is distributed with a divergent effect upon the entire mass, the formation of channels or liquid streams through the fiber being thus prevented.

I have also found that this effect may be augmented if not only the entrance perforations, but also the exit perforations, for the liquor be of this conical or expanding formation.

In order to determine the condition of the fibers at any period of the treatment operation, I have devised a small machine similar to the large one employed for treatment, so arranged that a sample of the fibers inserted therein will be subjected to the same treatment as those in the dyeing machine, and hence an examination of this sample will disclose the condition of the commercial dyeings without the trouble and loss of time incident to opening the large machine.

I have also devised a method whereby the temperature of the dye liquor may be readily observed.

One form of my device is shown in the accompanying drawings in which similar parts are designated by similar numerals.

Figure 1 is a side view of one form of my invention, partly broken away to disclose a portion in cross-section.

Fig. 2 is a broken cross section through the line 2—2 of Fig. 1.

Fig. 3 is a broken cross section through the line 3—3 of Fig. 1.

Fig. 4 is a fragment broken away of the tubes.

5 Fig. 5 is a broken cross section of a modification of one of the foraminous plates.

Fig. 6 is a top plan view of Fig. 5.

The dyeing machine comprises the cylindrical shell 7 and the cylindrical shell 8, 10 fixedly attached to each other by means of the bolts 9, 9, the cylindrical shell 8 being fixedly attached to the conical shell 10 by means of the bolts 11, 11. A foraminous plate 12 is integral with the shell 8. The 15 annular openings 14, 14 in the plate 12 are of a double truncated cone formation, the greater openings being upwardly and downwardly, thus having an outwardly expanding form, and are connected by the annular openings 15, 15, thus allowing of free passage through the plate 12.

Between the shells 8 and 10 is a foraminous plate 16 connected by means of the conical tubes 17, 17, to a foraminous plate 25 18 at the lower extremity of the shell 10. The formation of these two plates 16 and 18 and the conical tubes 17, 17 is shown enlarged in Fig. 4. The upper extremities 30 of the conical tubes 17, 17 are inserted in and fixedly attached to the plate 16, by brazing or other means, and the sides of the openings 19, 19, in the plate 16 above the tubes 17, 17 are flared outwardly to produce conical shaped openings.

35 The attachment and formation of the lower extremities of the tubes 17, 17 and the plate 18 are similar to those of the tubes 17, 17 and the plate 16.

The machine is provided with a removable annular foraminous plate 20, the openings 21, 21 of which are similar to the openings 15, 15 of the plate 12, said plate 20 fitting closely within the interior of the shell 7.

An annular angle shaped member 22 is 45 slidable within the shell 7, capable of abutment upon the plate 20 and maintained in any desired position by means of the thumb-screws 23, 23 which thread within the shoulders 24, 24 fixedly attached to the shell 7.

50 A rotary pump 25 is connected to the bottom portion of the shell 10 by means of the pipes 26, 27 which are fixedly attached to the shell 10 by means of the bolts 28, 28. A pipe 29, 30 connects the pump 25 with the 55 upper interior portion of the shell 7. A pipe 31 connects the pump 25 with a supply tank not shown and carries the valve 32.

60 The receptacle 33 is an exact smaller reproduction of the larger dyeing apparatus shown and described above with similar tubes and foraminous plates, the bottom portion of which is connected by means of the pipe 34 with the interior of the larger apparatus at a point between the plates 12

and 16. The upper end of the receptacle 65 33 is closed by means of the screw top 35, a pipe 36 connecting the interior of the upper portion of the receptacle 33 with the interior of the upper portion of the larger apparatus. The receptacle 33 and the pipes 70 34 and 36 are in exact proportion with the larger apparatus and the pipes 26 and 30.

It is evident that by closing the valve 55 the condition of the dyeing may be determined by examining the fiber in the receptacle 33 without interrupting the dyeing operation in the larger apparatus.

The pipe 37 is connected with the chamber 38 in which the thermometer 39 is inserted and the chamber 38 is connected with the 80 pipe 40.

The foraminous plate 12, as shown in Figs. 1 and 2, may be of other construction, one of which is shown in Figs. 5 and 6, in which the bars 41, 41 extend across the 85 plate, allowing the openings 42, 42.

A perforated steam pipe 43 is introduced into the receptacle formed by the plates 12 and 16.

The operation of the device is as follows: 90

The angle member 22 is loosed by means of the thumb-screws 23, 23 and removed from within the shell 7. The plate 20 is also removed. The fiber in the form of loose fiber, yarns, hanks, warps in the ball, tops 95 in the ball or in other condition, is packed evenly and thoroughly upon the plate 12, the plate 20 is introduced upon the fiber, and pressed thereon with considerable pressure by means of the angle members 22 and 100 the thumb-screws 23, 23, in order to make a compact mass of the fiber. The valve 32 is then opened and the dyeing liquor allowed to enter the pump 25 through the pipe 31. The pump 25 is started, forcing the dye liquor through the pipes 26, 27, the tubes 17, 17, the foraminous plate 16, the chamber 44, the foraminous plate 12, the chamber 45, and the foraminous plate 20 into the chamber 46, from which it flows through the 110 pipe 30, 29 back into the pump. When this stage is reached, the valve 32 is closed and the pump continues to circulate the liquid upwardly through the device and through the fiber. It is evident that when the liquor 115 passes from chamber 44 through the plate 12, it is not impinged against the fiber in chamber 45 in a series of separate streams with a direct upward force, but that it assumes the shape of the conical apertures and 120 is thus spread out and impinged against the entire lower surface of the fiber with a uniform pressure, thus causing it to pass equally through all parts of the mass. An equal pressure and distribution of the liquor is 125 maintained by having the plates 20, 12, 16 and 18 carry the double conical openings, as shown in the drawings.

The temperature of the dye liquor is determined by means of the thermometer 39 and governed by means of the steam pipe 43.

Before the dyeing operation is commenced, a proportionate amount of fiber to that in the large device is placed in the small receptacle 33 and the top 35 screwed down. During the dyeing operation, some of the dye liquor will be forced through the pipe 34 into the receptacle 33 and from there back into chamber 46 through the pipe 36. As the receptacle 33 and its connecting pipes are exactly proportionate to the larger ones, it is evident that the results to the fiber in the receptacle 33 will correspond to those in the larger apparatus, and the condition of the latter may be readily determined at any stage, without removing the plate 20, by removing the top 35 of the receptacle 33 and examining the fiber.

When the dyeing operation is completed, the dye liquor may be pumped back into the supply tank through the pipe 31, and wash water forced through the dyed fiber in the same manner as the dye liquor above described.

I do not limit myself to the size, shape, number or arrangement of the foraminous plates, tubes or other elements of my invention, all of which may be changed without going beyond the scope of my invention as described and claimed.

What is claimed, is:

1. In a dyeing machine, in combination, a receptacle having imperforate side walls, a foraminous plate having upwardly divergent openings within the receptacle, a second foraminous plate having downwardly divergent openings within the receptacle, a fiber chamber comprising the space between the plates and the imperforate sides of the receptacle, means for maintaining the two plates at varying distances from each other and capable of compressing fiber between the plates and the imperforate sides of the receptacle, and means for forcing liquid through the fiber chamber.

2. In a dyeing machine, in combination, a fiber chamber with imperforate sides, the bottom of which is a foraminous plate having upwardly divergent openings, a foraminous plate having downwardly divergent openings forming the top of the chamber, means for moving the plate with respect to the bottom plate and for compressing fiber between the two plates and the imperforate sides of the receptacle and for maintaining the plates in a predetermined position with respect to each other and means for forcing a liquid through the divergent openings of the one plate into the fiber chamber and through the openings of the other plate.

3. In a dyeing machine, in combination, a receptacle having imperforate side walls, a

foraminous plate having upwardly divergent conical-shaped openings, a second foraminous plate having downwardly divergent conical-shaped openings, a fiber chamber formed by the two plates and the imperforate sides of the receptacle, means for compressing fiber between the plates and the imperforate sides of the receptacle and means for circulating a liquid through the plates and the fiber chamber.

4. In a dyeing machine, in combination, a fiber chamber with imperforate sides, the bottom of which is a foraminous plate having upwardly divergent openings, a foraminous plate having downwardly divergent openings forming the top of the chamber, means for moving the top plate with respect to the bottom plate, and capable of compressing fiber between the two plates and the imperforate sides of the receptacle and for maintaining the plates in a predetermined position with respect to each other, a second chamber below the fiber chamber, having a foraminous bottom with upwardly divergent openings, an upwardly divergent tube integral with and opening into each of the openings of the foraminous bottom, and means for circulating a liquid through the tubes, the second chamber, the foraminous plates and fiber chamber.

5. In a dyeing machine, in combination, a receptacle having imperforate sides, a foraminous plate having upwardly divergent conical-shaped openings, a second foraminous plate having downwardly divergent conical-shaped openings, a fiber chamber formed by the two plates and the imperforate sides of the receptacle, means for compressing fiber between the plates and the imperforate sides of the receptacle, a second chamber below the fiber chamber having a foraminous bottom with upwardly divergent conical-shaped openings, a steam pipe within the second chamber, a series of upwardly divergent conical tubes integral with the openings in the bottom plate, a pump capable of forcing a liquid upwardly through the device and means for returning the liquid from the top of the receptacle to the pump.

6. In a dyeing machine, in combination, a receptacle, a foraminous plate with divergent openings movable within the receptacle, a second foraminous plate with upwardly and downwardly divergent openings spaced below the first plate, means for moving the first plate with respect to the second plate and for maintaining the movable plate at any desired position, a third foraminous plate with upwardly divergent openings spaced below the second plate, a fourth foraminous plate with downwardly divergent openings spaced below the third plate, tubes connecting the openings of the third and

fourth plates, and means for circulating a liquid continuously through the device.

7. In a dyeing machine, in combination, a receptacle, a foraminous plate with downwardly divergent openings movable within the receptacle, a second foraminous plate within the receptacle, a fiber chamber defined by the two plates and the sides of the receptacle, means whereby the first plate may be moved to decrease the size of the chamber and compress a fiber within the chamber, two foraminous plates having divergent openings spaced below the fiber chamber, tubular means connecting the openings of the two lower plates, a pump whereby a liquid may be forced through the device and fiber contained therein, and means whereby the liquid may be conveyed from the top portion of the device to the pump to allow of continuous circulation through the device.

8. In a dyeing machine, in combination, a receptacle having imperforate side walls, a foraminous plate having upwardly divergent openings within the receptacle, a second foraminous plate having downwardly divergent openings within the receptacle, a fiber chamber defined by the plates and the imperforate sides of the receptacle, means for maintaining the two plates at varying distances from each other and capable of compressing fiber between the plates and the imperforate sides of the receptacle, a smaller testing device similar and proportionate to, and exterior to, the larger device, means for connecting the spaces below the lower foraminous plates of the two devices and means for passing a liquid through said spaces, the connecting means, the first plates, the fiber chambers and the second plates.

9. In a dyeing machine, in combination, a fiber chamber with imperforate sides, the bottom of which is a foraminous plate having upwardly divergent openings, a foraminous plate having downwardly divergent openings forming the top of the chamber, means for moving the top plate with respect to the bottom plate and capable of compressing fiber between the two plates and the imperforate sides of the receptacle and for maintaining the plates in a predetermined position with respect to each other, a second chamber below the fiber chamber, having a foraminous bottom with upwardly divergent openings, an upwardly divergent tube integral with and opening into each of the openings of the foraminous bottom, a smaller testing device similar and proportionate to, and exterior to the larger device, means for connecting the spaces below the lower foraminous plates of the two devices and means for passing a liquid through the tubes, said spaces, the connecting means, the lower plate, the fiber chamber and the upper plate.

10. In a dyeing machine, in combination,

a receptacle having imperforate side walls, a foraminous plate within the receptacle, a second foraminous plate within the receptacle, a fiber chamber comprising the space between the plates, means for maintaining the two plates at varying distances from each other and capable of compressing fiber between the plates and the imperforate sides of the receptacle, a smaller testing device similar and proportionate to, and exterior to, the larger device, means for connecting the spaces below the lower foraminous plates of the two devices and means for passing a liquid through said spaces, the connecting means, the first plates, the fiber chambers and the second plates.

11. In a dyeing machine, in combination, a receptacle having imperforate side walls, a foraminous plate within the receptacle, a second foraminous plate within the receptacle, a fiber chamber comprising the space between the plates, means for maintaining the two plates at varying distances from each other and capable of compressing fiber between the plates and the imperforate sides of the receptacle, testing means whereby the condition of the fiber within the fiber chamber may be determined without removing the foraminous plates or interrupting the operation within the fiber chamber, means for forcing a liquid through the fiber chamber and the testing means in parallel.

12. In a dyeing machine, in combination, a fiber chamber with imperforate sides, the bottom of which is a foraminous plate having upwardly divergent openings, a foraminous plate having downwardly divergent openings forming the top of the chamber, means for moving the plate with respect to the bottom plate and for compressing fiber between the two plates and the imperforate sides of the receptacle and for maintaining the plates in a predetermined position with respect to each other, testing means exterior of the fiber chamber whereby the condition of the fiber within the fiber chamber may be determined without interrupting the operation within the fiber chamber, means for forcing a liquid through the fiber chamber and the testing means in parallel.

13. In a dyeing machine, in combination, a receptacle, a foraminous plate with divergent openings movable within the receptacle, a second foraminous plate with upwardly and downwardly divergent openings spaced below the first plate, means for moving the first plate with respect to the second plate and for maintaining the movable plate at any desired position, a third foraminous plate with upwardly divergent openings spaced below the second plate, a fourth foraminous plate with downwardly divergent openings spaced below the third plate, tubes connecting the openings of the third

and fourth plates, a testing device exterior to the fiber chamber capable of holding fiber, means for forcing a liquid through the fiber chamber and means for forcing a liquid from 5 the space between the second and third plates through the testing device.

Signed at Philadelphia, in the county of

Philadelphia and State of Penna., this 29th day of November, 1916.

HOWARD M. DUDLEY.
